UNITED STATES PATENT OFFICE.

DAVID E. GRAY, OF NEW YORK, N. Y.

ELECTRIC SWITCH.

No. 893,160.

Specification of Letters Patent.

Patented July 14, 1908.

Application filed April 26, 1905, Serial No. 257,439. Renewed June 29, 1907. Serial No. 381,548.

To all whom it may concern:

Be it known that I, DAVID E. GRAY, a citizen of the United States, residing at the city, county, and State of New York, have invented 5 certain new and useful Improvements in Electric Switches, of which the following is a full, clear, and exact description.

My invention relates to improvements in electric switches, and particularly to small 10 arm or lever switches. It will be obvious, however, that the size of the switch is immaterial.

The object of the invention is to provide a simple construction which cannot be readily 15 tampered with or put out of order, but which may be readily adjusted for providing instant connection with a circuit from one or more batteries, either singly, in series, or in multiple.

20 The two accompanying sheets of drawings illustrate a construction for carrying out the principles of my invention.

Briefly, it may be said to consist of a base member, a stationary main terminal, a movable plate terminal, which may be adjusted so as to permit throwing of either one of two batteries into circuit, or both batteries in circuit in multiple, or both batteries in circuit in series, and a switch lever for connecting 25 the terminals at will. The adjustable contact member may also be removed from the base so as to prevent tampering with the switch when it is not desired to have the circuits closed.

30 Figure 1 is a plan view of a switch embodying the improvements of my invention, shown with simple circuit connections so that two batteries may be thrown into circuit alone or in multiple. Fig. 2 is a se- 35

tional view of the same on a vertical plane. Fig. 3 is a detail on a large scale showing the movable terminal plate. Fig. 4 is a detail end view of the post of the same. Fig. 5 is a detail side view of one of the contact arms.

40 Fig. 6 is a detail end view of the other contact arm. Fig. 7 is a bottom view of a switch embodying the improvements of my invention, with connections for permitting two batteries to be thrown into circuit either 45 singly, in multiple, or in series. Fig. 8 is a 50 sectional view of the same taken on the plane of the line X—X of Fig. 7.

55 #1 and #2 represent batteries or sets of batteries, which it is desired to connect in circuit with some device such as a spark coil 3, where the work is to be performed. It is

sometimes desired to connect one battery in circuit, sometimes the other, and sometimes both batteries. By my construction this may be done in a very simple manner. Fig. 60 1 illustrates circuits necessary for connecting these batteries either singly or in multiple. By the circuit shown in Fig. 7 the batteries may be further combined in series. The visible accessible parts of the device, however, are the same for either method of connection, the only difference being in the connections and in the extent of adjustment of one of the terminal members.

65 4 is a base conveniently of insulating material for carrying the various parts of the switch proper.

70 5 represents the main terminal which is connected to the work 3.

75 6 represents a contact plate, which is provided with means of connection with the other leads of the batteries.

7 is a swinging switch lever for connecting the main terminal to the contact plate. The terminal plate 6 is preferably provided with a 80 groove having a sharp outside edge or wall for the better holding the switch lever in place.

8 is a stop pin for the switch lever in its 85 "off" position.

9 9 is a stop pin carried by the terminal plate 6 for limiting the movement of the switch lever in the "on" position.

10 and 11 are clamping posts or terminals 90 for the battery leads.

12 and 13 are spring contact members connected respectively to the posts 10 and 11 and arranged concentrically with the pivot post 14 of the member 6. The contact members 22 and 23 are connected together by the 95 arm 24 in the multiple and #1 positions of the switch, while the contact members 12 and 22 are connected by the arm 24 in the series position.

15 is an arm carried by the post 14 and 100 electrically connected thereto, and having a shoulder 16 resting in a recess 16' of the post 14 for preventing the parts from turning independently of one another.

17 is a screw for clamping the parts. The 105 arm 15 may thus be brought into contact with the members 12 or 13 by oscillating the member 6. When the arm 15 engages the member 12 and the switch lever 7 connects the members 5 and 6, battery #1 is in circuit 110 with the work 3. When the arm 15 engages the contact member 13, battery #2 is adapt-

ed to be thrown in or out of circuit by the simple operation of the lever 7. When the arm 15 bridges the two contact members 12 and 13, both batteries #1 and #2 are in circuit in parallel with the work.

If it is desired to wire the switch so that the batteries in addition to multiple connection may have series connection, the circuit will be as shown in Fig. 7.

10 20 and 21 are clamping posts or terminals for the battery leads. 22 and 23 are spring contact members connected thereto respectively.

24 is an arm carried by the post 14, but insulated therefrom, and having a shoulder 25 adapted to rest in the recess 25' to prevent the parts from turning relatively to one another. The plate 6 in the form shown has a notch in its edge and a dial is arranged or 20 laid out on the surface of the base around the plate and bearing the indices or marks 1, 2, M, and S. When the member 6 is oscillated to bring the notch in its edge opposite a mark on the dial, the connection indicated opposite, may be instantly established by swinging the lever 7, the operation of the lever being identically the same for establishing any of the connections for which the switch may be adapted. When the notch is 30 opposite 1 on the dial, connection is made to battery #1; when opposite 2 connection is to battery #2; when opposite M the batteries are in multiple, and when opposite S the batteries are in series. The base may 35 be cut away to permit of the removal of the member 6 with its arms 15 and 24, so that the switch cannot be tampered with.

The advantages of this construction will be apparent to those skilled in this art.

40 What I claim is:

1. In an electric switch, the combination of a base, a terminal member, a contact member, and a switch lever for connecting said members, one of said members being 45 adjustable and means coöperating therewith for effecting connections with a plurality of batteries either singly or in multiple.

2. In an electric switch, the combination of a base, a terminal member, a contact member, and a switch lever for connecting said members, one of said members being 50 adjustable and means coöperating therewith for effecting connections with a plurality of batteries either singly or in series.

55 3. In an electric switch, the combination of a base, a terminal member, a contact

member, and a switch lever for connecting said members, one of said members being adjustable and means coöperating therewith for effecting connections with a plurality of 60 batteries either singly, in multiple or in series.

4. In an electric switch, the combination of a base, having an opening, a stationary main terminal carried by said base, a switch lever pivoted to said main terminal, a contact member, a post projecting therefrom and through said opening, and a contact arm carried by the post of said contact member beneath said base and removable through said 70 opening.

5. In an electric switch, the combination of a base, a terminal member, a contact member, a switch lever for connecting said members at will, one of said members being 75 pivoted and means carried beneath said base for affording different electrical connections, depending on the position thereof.

6. In an electric switch, a base member, a pivoted lever carried thereby and adapted to 80 form a part of the electric circuit, a plate pivotally carried by said base, and a projecting stop post carried by said plate for limiting the movement of said switch lever.

7. In an electric switch, the combination 85 of a pivoted contact lever and a pivoted contact plate engaged thereby with means for different electrical connections controlled by said plate.

8. In an electric switch, a base, two battery contacts carried thereby, a pivoted member on one side of the base for engaging either one of said contacts, a post supporting said member and extending through said base, a main terminal and a second pivoted 95 member on the side of the base opposite the first mentioned pivoted member, said second pivoted member being adapted to connect and disconnect said main terminal and said post.

9. In an electric switch, a base, common and separate battery terminals carried thereby, two swinging members for connecting said terminals, one of said members being above and the other being below the base 105 and an extension from the latter through the base.

DAVID E. GRAY.
